UNITED STATES PATENT OFFICE

FRANK W. YEAGER, OF GRANTWOOD, AND WILLIAM P. SCHULZ, OF GUTTENBERG, NEW JERSEY, ASSIGNORS TO THE BARRETT COMPANY, A CORPORATION OF NEW JERSEY

SHINGLE-LOCKING DEVICE

Application filed July 18, 1924. Serial No. 726,660.

This invention relates to a flexible shingle which may be of the sort that is commonly made by saturating a base of so-called felted fibrous material with a saturant such as asphalt, then, covering this saturated base with a plastic layer, such as asphalt or the like, and thereafter applying wear resisting material such as crushed stone, slate etc. Sheets of roofing material of this sort are usually cut into shingles or shingle strips and laid on a roof in the usual manner. When these shingles are square or rectangular in shape, and are installed with one corner extending in a downward direction, there often times exists a tendency for the corners to curve or turn up. By the present invention this tendency is overcome and shingles may be laid in such a manner that they are locked down with no danger of the same being turned up by the wind or otherwise curling up.

The invention will be understood from the following description taken in connection with the accompanying drawings in which

Fig. 1 is a plan view of one of the shingles.

Fig. 2 is a plan view showing how several shingles are installed on the roof.

Fig. 3 is an end view partly broken away, showing the relative position of some of the shingles as installed.

Fig. 4 is a plan view of a modification of the locking device.

In the drawings reference character 1 represents a shingle which has two of its opposite corners cut away as shown at 2. A

short distance from one of the other corners 4, notches are cut into the edges of the shingles along lines 5 perpendicular to the edges and lines 6 parallel to the diagonal joining the corners 3 and 4. In this way a

tab is left at one corner 4 of the shingle and two smaller tabs 7 and 8 are left adjacent thereto. The tab including the corner 4 may be turned under along the dotted line 9 at the upper ends of the notches in the edges

of the shingle. A locking device 10 which may be made of wire having eyes at each end thereof, or may be made of a thin strap 11

(Fig. 4) which has holes at the ends thereof, may be fastened by a fastener 10' near one of

the cut away corners 2 as shown in Fig. 1.

While this shingle is being shipped, this locking strip 10 may be turned so as to lie within the area of the shingle so as not to interfere with packing the same in bundles.

When it is desired to install these shingles on a roof, they may be laid in horizontal rows with the cutaway corners 2 of adjacent shingles spaced a short distance apart or a sufficient distance apart so that the tab at the corner 4 of another shingle can be placed between them. As the shingles are being laid in horizontal rows the locking strips 10 are placed so as to bridge the space there-between, and nails or fastening devices 12 and 13 are passed there-through into the roof deck, as more clearly shown near the upper portion of Fig. 2. The tabs include the corners 4 of shingles that are to be installed in the next higher row, and are turned under and inserted under the locking strips 10 between the cutaway corners 2 of shingles in the preceding row of shingles. These tabs are slipped upwardly until the bent portion along the line 9 reaches the locking strips 10 whereupon the smaller tabs or shoulders 7 and 8 will lie upon and conceal the nails or fastening devices 12 and 13 and one side of these tabs 7 and 8 will be flush with the edges of underlying shingles as is clearly seen in Fig. 2.

It will be seen that by this invention a very simple and secure lock for the lower portion of shingles is provided, there is practically no loss in cutting the shingles from a sheet of roofing material, the shingles can be conveniently packed, and present an attractive pattern when they are installed upon the roof.

We claim:

1. A flexible shingle having two notches in two adjacent edges thereof forming one intermediate and two side tabs, one side of each of said notches being substantially perpendicular to the edge in which it is formed, and the other sides being substantially parallel to each other the intermediate tab being turned under to form a fastener engaging hook and the side tabs extending in the plane of the body of the shingle.

2. A flexible shingle having a central pointed tab formed at its lower end and a tab on each side of, and adjacent to said first named

tab, the respective sides of the outer extremities of said tabs being parallel to each other the central tab being turned under to form a retaining hook and the side tabs extending in the plane of the body of the shingle.

5 3. In a roof, shingles having turned under corners and cut away corners, fastening devices secured to and extending between cut away corners in a horizontal row, said turned under corners in one row concealing and being held by said fastening devices in a lower row.

10 4. In a roof, shingles having three tabs on one corner thereof one of said tabs being turned under, a fastener for said tab secured to and extending between adjacent cut away corners of other shingles, the other tabs covering the ends of said fastener.

15 5. A flexible shingle having notches in its edges near one corner forming a central tab and having the adjacent corners cut away, and a fastener attached to said shingle near a cut away corner and adapted to be fastened to an adjacent shingle near a cut away corner, the central tab being turned under to form a hook to engage and conceal the fastener of another shingle.

20 6. A shingle having its lower portion formed with downwardly converging side edges, said shingle having two laterally spaced apart downwardly projecting tip members at its lower extremity, and an undeturned tab member folded on a line connecting the base portions of said tip members.

25 7. A shingle cut inwardly substantially at right angles to the opposite edges of the shingle adjacent the lowermost corner portion thereof, and said corner portion being turned under the shingle on a line of fold extending between the inner ends of the cuts, whereby downwardly projecting tips are provided on the shingle at the opposite ends of the line of fold of the undeturned corner tab member.

30 8. In a roof, shingles having parallel-sided tabs turned under to form fastener engaging hooks, the turned under tabs in one row extending between the cut away corners of the shingles of a lower row.

35 9. In a roof, shingles arranged in rows, the shingles of each row being spaced laterally, and fastening devices bridging the spaces and connecting the shingles, each shingle having at its lower edge a turned under tab forming a hook of substantially the width of the space between the shingles of a lower row and engaging and concealing a fastening device.

40 10. In a roof, shingles arranged in rows, the shingles of each row being spaced laterally, and bar fasteners bridging the space between adjacent shingles connecting the shingles to each other and to the roof, each shingle having at its lower edge a turned under tab forming a hook extending beneath the fas-

tener of a lower row and between the adjacent shingles secured by said fastener.

In testimony whereof we affix our signatures.

FRANK W. YEAGER.
